1.7 : Bottom

1.8 : Reference

The present design is a cushion for infants. Especially, the present design is shaped with the shape of the alphabet B as a motif, and it wraps the baby as a whole and supports the back and belly to prevent the baby from falling back and forth. The present design is designed so that the baby can be laid down alternately without distinction of up, down, left and right directions. The broken lines in the drawings depict environmental subject matter that forms no part of the claimed design.
